UNITED STATES PATENT OFFICE

170,246

PREFORMED NECKTIE

Philip F. Spaniol, Baltimore, Md.

Application October 19, 1951, Serial No. 17,027

Term of patent 7 years

(Cl. D3—16)

To all whom it may concern:

Be it known that I, Philip F. Spaniol, a citizen of the United States, residing at Baltimore city, State of Maryland, have invented a new, original, and ornamental Design for a Preformed Necktie of which the following is a specification, reference being had to the accompanying drawing, forming a part thereof, in which:

The essential features of my design reside in the portions shown in solid lines.

I claim:

The ornamental design for a preformed necktie, as shown and described.

PHILIP F. SPANIOL.
